Inventor:
George R. Brown
by *Wm. F. Jones*
His Attorney.

UNITED STATES PATENT OFFICE.

GEORGE R. BROWN, OF BRIDGEPORT, CONNECTICUT, ASSIGNOR TO GENERAL ELECTRIC COMPANY, A CORPORATION OF NEW YORK.

ELECTRIC FUSE.

Application filed July 20, 1926. Serial No. 123,732.

The present invention relates to electrical safety devices, and more particularly to enclosed fuses. The object of the invention is to provide an improved construction of fuse 5 which shall operate satisfactorily under severest current conditions, to interrupt the circuit protected thereby and without danger of injury to persons or things.

When a fuse operates or blows under 10 short-circuit conditions, its fusible element is converted in an extremely limited period of time into metallic gas of such high heat that persons and combustible matter in the vicinity would be burned or otherwise injured if provision is not made to confine such 15 gas until its heat has become dissipated to a considerable extent. Accordingly, it is customary to enclose electrical fuses in plugs or cartridges of insulating material, and, on 20 account of the liability of the high gas pressure generated, to disrupt the insulating enclosure it is customary to provide the latter with vents whereby the gas may escape gradually.

25 In order that the presence of the vents may not nullify the purpose of the insulating enclosure, I so arrange the vents that as gas passes from the insulating enclosure it impinges upon and is allowed to expand in contact with metal surfaces which serve to deprive it of most of its heat, and it is then directed in its final escape into the atmosphere so that particles of metallic oxide contained 30 therein are deposited on the outer end of the encasement and serve as an indication that 35 the fuse has blown.

One embodiment of the invention is shown in the accompanying drawing, in which Fig. 1 is a vertical section of a fuse plug shown 40 about double usual size, and Fig. 2 is a top plan thereof with parts broken away.

As shown in the drawing, the plug comprises a cup-shaped base 1 of porcelain or other insulating material with a screw shell 45 contact 2 and a center contact 3 mounted thereon in well-known manner and connected by a fuse link 4 of soft metal. The cup-shaped base has at its upper end an integral external flange 5 with its top corner 6 chamfered, and one or more narrow vent slots or 50 passageways 7 are cut radially across the upper end wall of the base.

An imperforate disk 8 of transparent insulating material, such as mica, and of a 55 size somewhat less than that of the base

flange 5, is securely bound against the upper end of the base by a metal closure shell 9.

The metal closure shell 9 has a peripheral down-turned flange 10 of a size to closely surround the base flange 5, and is secured in 60 place by spinning its lower edge 11 beneath the base flange 5. The center of the shell 9 is apertured at 12 to permit inspection of the condition of the fuse link 4 through the transparent disk 8. The aperture 12 is made 65 relatively small in order that the greater part of the transparent disk may be sustained against the gas pressure within the plug by the metal shell 9.

The radial portion of the metal shell 9 is 70 provided with two spaced annular beads 13 and 14 adjacent its periphery and about the central aperture 12, respectively, and the plane portion 15 between the beads has a plurality of radial embossments 16 struck 75 up therein which connect with the outer bead 13 and extend to slits 17 cut adjacent the inner bead 14 whereby inwardly directed exits from the gas expansion space 18 formed between the base chamfer 6 and the inside 80 of the outer bead 13 are provided.

Upon blowing of the link 4, the gases generated thereby pass in a small stream or streams through the narrow vent slot or slots 7 at the upper end of the base, beneath 85 the transparent disk 8, and impinge against the inner wall of the flange 10 of the metal shell 9 which acts to absorb much of the heat thereof, and after becoming expanded within the space 18 they escape through the 90 inwardly directed exits of the radial embossments 16 and impinge upon the outer wall of the inner bead 14 whereby they are deflected centrally along the axis of the plug so that they can make no objectionable 95 deposits on the cut-out block in which the fuse is installed. On account of the gases containing particles of oxidized metal, the latter forms black deposits 19 upon the wall of the bead 14, and thereby affords an indication 100 of the fact that the fuse has blown, which may be readily observed even in dimly lighted places.

While I have shown and described the best embodiment of the invention known to me, I 105 do not desire to be restricted thereto.

What I claim as new, and desire to secure by Letters Patent of the United States, is:

1. An electric fuse comprising an insulating base provided with a gas passageway, 110

and a metal shell enclosing an end of said base and the passageway therein, said shell forming with said base an expansion chamber for the gases and having in the wall thereof inwardly opening exit passages from said chamber.

2. An electric fuse comprising an insulating base provided with a vent passageway and an end flange, and a sheet metal shell enclosing an end of said base and the passageway therein and secured to said end flange, said shell being beaded adjacent its periphery to form with the base a gas expansion chamber and having in the end wall thereof inwardly directed exit passages from said chamber.

3. An electric fuse comprising an insulating base provided with a gas passageway, and a metal shell enclosing an end of said base and the passageway therein, said shell forming with said base end a gas expansion

chamber and having formed in the end wall thereof inwardly directed exit passages from said chamber and an outwardly inclined surface against which the exit gases impinge.

25

4. An electric fuse comprising an insulating base having at its end a vent passageway and a peripheral flange, a transparent disk over the end of said base, and a sheet metal shell having a central aperture secured over said base flange and holding said disk thereto, said shell having spaced beads struck up therein adjacent its periphery and about the aperture therein and inwardly directed exit passages extending from the interior of the peripheral bead and opening adjacent the outer wall of the bead about the central aperture thereof.

30

In witness whereof, I have hereunto set my hand this sixteenth day of July, 1926.

GEORGE R. BROWN.
